LOCK

Adolf Schoepe, Anaheim, and John White Sinclair, Costa Mesa, Calif., assignors to Kwikset Locks, Inc., Anaheim, Calif., a corporation of California

Application March 30, 1950, Serial No. 152,863

10 Claims. (Cl. 292—66)

1

This invention relates to improvements in locks, such as door locks.

A primary object of the invention is to provide an improved door lock wherein there is an advanceable and retractable bolt movable into and out of a keeper, the bolt having a head receivable through a large portion of the opening in the keeper and which, after the bolt has been advanced into the keeper through the large portion of the opening therein has the bolt tilted or shifted into a position wherein the head of the bolt occupies a position behind a narrower portion of the opening in the keeper. In this manner as the head on the bolt is effectively locked in the keeper against withdrawal therefrom as long as the bolt is in the tilted position the improved lock may be advantageously employed between two opposed swinging doors or between slideable doors or a slideable door and its door jamb.

More specifically, an object of the invention is to provide a lock having the above-mentioned characteristics wherein the bolt is projected from its housing in an axial direction and after having been projected therefrom a sufficient distance to enter the keeper bolt is tilted with relation to the housing and keeper and is effectively locked in the tilted position until unlocked therefrom in a proper or authorized manner, such as by the reverse operation of the plug of a key-controlled lock.

Another object of the invention is to provide a lock having the above-mentioned characteristics wherein a number of precautionary measures are taken to prevent unlocking of the bolt when in its locking position either by reverse working on the bolt itself, jarring, vibration or the like, and to provide a lock which will function properly regardless of whether the lock is installed in a right side up position or an upside down position.

With the foregoing and other objects in view which will be made manifest in the following detailed description and specifically pointed out in the appended claims, reference is had to the accompanying drawings for an illustrative embodiment of the invention, wherein:

Figure 1 is a horizontal section through a portion of a door and either an opposed door or a door jamb therefor, illustrating the lock and its keeper embodying the present invention as having been installed thereon;

Fig. 2 is a vertical section through the lock housing and the keeper, the bolt of the lock being shown in its fully retracted position;

Fig. 3 is a horizontal section taken substantially upon the line 3—3 upon Fig. 2;

2

Fig. 4 is a view similar to Fig. 2, but illustrating the lock in that position wherein the bolt has been projected from the housing into the keeper, the position of the bolt being roughly halfway between the fully retracted position and the fully projected position;

Fig. 5 is a view similar to Fig. 2, but illustrating the bolt of the lock in fully projected position;

Fig. 6 is a vertical section taken substantially upon the line 6—6 of Fig. 5 in the direction indicated; and

Fig. 7 is a vertical section taken substantially upon the line 7—7 of Fig. 5 in the direction indicated.

Referring to the accompanying drawings wherein similar reference characters designate similar parts throughout, the improved lock consists generally of a housing 10 adapted to be recessed in a door D and which has preferably integral therewith a face plate 11 adapted to be recessed in the edge of the door.

The keeper for the bolt of the lock consists of a receptacle or cup 12 adapted to be recessed either in an opposed door or in a door jamb J and this receptacle is equipped with a face plate 13 in which an opening is formed. The opening in the face plate 13 is generally of keyhole configuration, that is the upper portion of the opening indicated at 14 is of sufficient width and size to enable the head 15 of the bolt 16 to be passed therethrough. The lower portion of the opening in the face plate 13 indicated at 17 is narrower than the upper portion so that the head 15 cannot be retracted through the lower portion of the opening. The lower portion of the opening, however, is capable of receiving the shank of the bolt 16 behind the head 15.

The shank of the bolt extends rearwardly in a cavity 18 cored or otherwise formed in the housing 10. Intermediate its ends a diametrical slot 19 is formed through the shank of the bolt and a pin 20 extends transversely through the housing and through the slot 19. The length of the slot 19 is equal to the length of the throw of the bolt 16 and the pin 20 extending through the slot while guiding to a certain extent the movement of the bolt enables the bolt not only to slide with relation to the housing but to tilt relatively thereto. The forward end of the housing is relieved as indicated at 21 to accommodate a downward tilting of the bolt as viewed in Fig. 5.

Behind the bolt 16 there is a plug 22 that is slideable in the cavity 18. Two pins 23 and 24 extend laterally from this plug and a similar pin 25 extends laterally from the bolt 16. A gate or

plate 27 lies against the sides of the bolt and plug. This plate or gate is pivotally connected to the rear end of the bolt by means of the pin 25 thereon. However, it has a three-armed slot formed therein receiving the pins 23 and 24. The arms 5 of this slot are indicated at 28, 29, and 30, respectively. When the bolt and plug are in their fully retracted positions the pin 23 occupies a position near the extreme end of the arm 30 and the pin 24 occupies a position intermediate the arms 28 10 and 29 as viewed in Fig. 2. In the course of shifting of the bolt the pin 24 moves from the position shown in Fig. 2 to the extreme end of the arm 29 as it is shown in Fig. 5. The pin 23 is withdrawn from the arm 30 and starts to enter the arm 28. 15 The adjacent ends of the plug 22 and the bolt 16 are bifurcated to receive a link 22a which is pivotally connected to the plug and bolt respectively by the pins 24 and 25.

A link 31 lies against the outer side of the gate or plate 27, this link having an elongated opening 32 at one end through which the pin 23 extends. The elongated opening provides a slight amount of lost motion between the link 31 and the pin on the plug. The link in turn is pivotally connected as at 33 to a crank arm 34 on a rotary spindle 35 that extends transversely through the housing. This spindle may be operated in any suitable manner such as by the rotatable plug of a key-controlled cylinder lock, such locks being indicated on opposite sides of the door D at 36 and 37. Any other suitable means for controlling the rotation of the spindle 35 so that it can only be rotated in an authorized manner may be utilized.

In the housing there is a ball 38 behind which there is a compressible material such as rubber 39 retained in position such as by a plug 40. This ball is disposed within a bore in the housing the edges of which are peened over or otherwise formed to retain the ball in a position wherein it partially projects from the body of the housing so as to be engageable with the rear face of the crank arm 34, serving to retain the crank arm in its fully thrown position shown in Fig. 5 unless forcibly disturbed from that position. A recess is formed on the rear face of the crank arm to partially receive the ball so that it may function as a detent. As will be noted, the crank arm carries near the spindle a small cam 41 which, in the course of the operation of the lock, is engageable with the curved edge portion of the gate indicated at 42 so that as the parts proceed from the position shown in Fig. 4 to the position shown in Fig. 5, the gate 27 will be positively tilted upwardly. Conversely, in reversely operating the lock from the position shown in Fig. 5 to the position shown in Fig. 4, the cam 41 will engage the surface 42 to start a swinging of the gate 27 relative to the bolt 16 or about the pin 25 as a center to cause the plug 22 to assume a position ahead of the bolt 16 in the course of retracting the bolt. After the cam 41 has started a reverse swinging of the gate 27 from the position shown in Fig. 5, thus causing the pin 23 to re-enter the arm 30, the force exerted by the link 31 on the pin 23 causes the plug 22 to be forced rearwardly in the cavity 18 and the pins 23 and 24 quickly resume their positions with respect to the arms in the gate, as depicted in Fig. 4.

The parts of the lock are confined within the housing by means of a cover 43, the interior of which is shaped so as to slidably bear upon and guide the parts confined thereby. At the top of the cavity 18 there is an inclined recess 44, 75

which in addition to communicating with cavity 18 is formed in a portion of housing 10, which accommodates the rear end of the bolt 16 when the bolt is tilted. This recess is provided with a shoulder 45, being a depending portion of the housing, engageable by the rear end of the bolt when the bolt is in tilted position and which will prevent reverse movement of the bolt from its projected position unless the spindle 35 is reversely rotated. Below the recess 45 the housing provides a shallow recess 46 which accommodates the forward end of the plug 22 when the plug is in tilted position shown in Fig. 5.

The operation of the above-described lock is substantially as follows:

If the spindle 35 is rotated in a counterclockwise direction as viewed in Fig. 2, its crank arm 34 will cause the link 31 to draw the plug 22 from right to left by reason of the engagement of the link 31 with the pin 23 on the side of the plug. During the initial forward movement of the plug the plug is confined by the cavity 18 and as the pin 23 is at the extreme rear end of the arm 30 of the slot motion can be transmitted by the gate or plate 27 from the plug 22 to the bolt 16. During the initial forward movement of the bolt, the bolt merely slides in an axial direction projecting its head 15 through the wide upper portion of the opening in the keeper 13. Such movement continues through and beyond the position shown in Fig. 4. However, as the rotation of the spindle continues from the position shown in Fig. 4 to the position shown in Fig. 5 the edge 42 will engage the cam 41 causing the gate 27 to be tilted upwardly. This causes the rear end of the bolt 16 to move upwardly into the recess 44 and causes the bolt to tilt about the pin 25 as a center. The upward tilting of the bolt affords an opportunity for the plug 22 to slip beneath the bolt and to enter the cavity 46 and in the course of this tilting movement of the plug 22, its pins 24 and 23 assume positions at the extremities of the arms 29 and 28 of the slot in the gate. In this position the plug functions somewhat as a wedge occupying the space between the bottom of the tilted bolt 16 and the bottom of the cavity 46. When the crank arm 34 reaches its extreme position as illustrated in Fig. 5, the detent or ball 38 will be engaged which serves to retain the crank arm and its spindle in the thrown position until forcibly dislodged therefrom.

During the opening movement of the lock, that is reverse rotation of the spindle 35 from the position shown in Fig. 5 to the position shown in Fig. 2, the initial movement of the crank arm causes the cam 41 to engage the edge 42 and to commence swinging the gate 27 in a counterclockwise direction about the pin 25. This causes the plug 22 to commence to move in a reverse direction in the cavity 18 in advance of the bolt 16. During such movement the pins 23 and 24 start returning to the positions shown in Figs. 2 and 4 in the three-arm slot. Continued clockwise rotation of the crank arm 34 causes the link 31 to push the plug 22 to the rear end of the cavity and the gate 27 to pull the bolt 16 downwardly from the tilted position and to be retracted in an axial direction.

It will, of course, be appreciated that in the course of the operation of the lock that the head 15, after passing through the large portion of the opening in the keeper, then moves downwardly behind the narrow portion of such opening so that it cannot be withdrawn therefrom as long

as the bolt is in the tilted position, thus making the head of the bolt self-locking within the keeper. Such an arrangement makes the improved lock highly suitable for use on sliding doors and on so-called double doors. When in locking position it is impossible to work the bolt 16 rearwardly because of its engagement at its rear end with the shoulder 45. It is likewise impossible to turn the bolt from its tilted position due to the wedging effect of the plug 22 between the bottom of the bolt and the bottom of the recess 46. Jarring or vibration of the lock will not result in an unauthorized retraction of the bolt due to the pins 24 and 23 occupying positions at the extremities of the arms 29 and 28 of the slot in the gate. Likewise the spindle 35 cannot be induced to turn by jarring or vibration because of the restraining effect of the detent ball 38. The improved construction is such that even if the lock is installed in an upside down position from the position shown that it is impossible to effect an unauthorized retraction of the bolt in either of the manners above referred to.

It will be appreciated by those skilled in the art that the improved lock is very positive in its operation and is composed of a relatively small number of parts which, because of various functions that they assume, provide adequate locks against unauthorized movements of any parts.

Various changes may be made in the details of construction without departing from the spirit and scope of the invention as defined by the appended claims, wherein:

We claim:

1. A lock comprising a housing, a headed latch bolt mounted for sliding and tilting movement therein, a keeper having a keyhole type opening therein through the large end of which the head of the latch bolt may be projected and then on tilting of the latch bolt the small end of the opening may serve to retain the head therein, a plug slidable in the housing behind the latch bolt, and means connecting the plug and latch bolt for causing the plug and latch bolt to move together towards bolt-projecting position and then to tilt the latch bolt relative to the housing and cause the plug to enter between the latch bolt and the housing to lock the latch bolt in its tilted position.

2. A lock comprising a housing, a headed latch bolt mounted for sliding and tilting movement therein, a keeper having a keyhole type opening therein through the large end of which the head of the latch bolt may be projected and then on tilting of the latch bolt the small end of the opening may serve to retain the head therein, a plug slidable in the housing behind the latch bolt, and means connecting the plug and latch bolt for causing the plug and latch bolt to move together towards bolt-projecting position and then to tilt the latch bolt relative to the housing and cause the plug to enter between the latch bolt and the housing to lock the latch bolt in its tilted position, the housing presenting a shoulder engageable by the latch bolt when in tilted position to prevent retraction of the latch bolt while held locked by the plug in tilted position.

3. A lock comprising a housing, a latch bolt mounted for sliding movement into projected and retracted positions relative to the housing and for pivotal movement relative thereto when in projected position, a plug normally disposed

behind the latch bolt in the housing, means for moving the latch bolt and plug in unison from bolt retracted position to bolt projected position, and then causing the plug to enter between the housing and the bolt when the bolt is in its projected and tilted position to lock the bolt in its tilted position.

4. A lock comprising a housing, a latch bolt mounted for sliding movement into projected and retracted positions relative to the housing and for pivotal movement relative thereto when in projected position, a plug normally disposed behind the latch bolt in the housing, means for moving the latch bolt and plug in unison from bolt retracted position to bolt projected position, and then causing the plug to enter between the housing and the bolt when the bolt is in its projected and tilted position to lock the bolt in its tilted position, the housing presenting a shoulder engageable by the bolt when the bolt is in its tilted position to prevent retraction of the bolt while in its tilted position.

5. A lock comprising a housing, a spindle therein, a crank arm swingable by the spindle, a latch bolt movable in the housing from retracted to projected position and vice versa, and tilttable relative to the housing while in projected position, a plug movable in the housing and normally disposed behind the latch bolt, a link pivotally connected to the crank arm and to the plug, and a gate pivotally connecting the plug and latch bolt.

6. A lock comprising a housing, a spindle therein, a crank arm swingable by the spindle, a latch bolt movable in the housing from retracted to projected position and vice versa, and tilttable relative to the housing while in projected position, a plug movable in the housing and normally disposed behind the latch bolt, a link pivotally connected to the crank arm and to the plug by a pivot pin, and a gate pivotally connecting the plug and latch bolt, the gate having a three-armed slot through one arm of which the pivot pin connecting the link to the plug extends, the plug also having a pin extending through the slot and shiftable into one of the other arms thereof.

7. A lock comprising a housing, a spindle therein, a crank arm swingable by the spindle, a latch bolt movable in the housing from retracted to projected position and vice versa, and tilttable relative to the housing while in projected position, a plug movable in the housing and normally disposed behind the latch bolt, a link pivotally connected to the crank arm and to the bolt, and a gate pivotally connecting the plug and latch bolt, a cam on the crank arm engageable with an edge on the gate, said cam being arranged so as to produce swinging movement of the gate when the gate is engaged thereby.

8. A lock comprising a keeper having a key-hole opening therein, a housing, a headed latch bolt in the housing adapted to be projected therefrom into the keeper, a spindle rotatable in the housing, and means operable by the spindle for advancing the latch bolt in an axial direction and then swinging the latch bolt into a position engaging a shoulder in the housing and into a position wherein the head on the latch bolt is behind the narrow portion of the keyhole opening in the keeper, the shoulder being arranged to oppose axial retracting movement of the bolt.

9. A lock comprising a keeper having a key-

hole opening therein, a housing, a headed latch bolt in the housing adapted to be projected therefrom into the keeper, a spindle rotatable in the housing, and means operable by the spindle for advancing the latch bolt in an axial direction and then swinging the latch bolt into a position engaging a shoulder in the housing and into a position wherein the head on the latch bolt is behind the narrow portion of the keyhole opening in the keeper, the shoulder being arranged to oppose axial retracting movement of the bolt and wedge means operable by the spindle for wedging the latch bolt in its tilted position until the spindle is reversely rotated.

10. A lock comprising a keeper having a key-hole opening therein, a housing, a headed latch bolt in the housing adapted to be projected therefrom into the keeper, a spindle rotatable in the housing, means operable by the spindle for advancing the latch bolt in an axial direction and then swinging the latch bolt into a position engaging a shoulder in the housing and

15
5

into a position wherein the head on the latch bolt is behind the narrow portion of the keyhole opening in the keeper, the shoulder being arranged to oppose axial retracting movement of the bolt wedge means operable by the spindle for wedging the latch bolt in its tilted position until the spindle is reversely rotated, and a detent engageable with a part carried by the spindle for retaining the spindle in that position assumed by the spindle when the latch bolt is fully projected.
